ABSTRACT

An apparatus (10) for proportioning and mixing liquid components of a solvent has a chamber (12) with a rotatable piston (24) mounted in the chamber. The chamber has a plurality of liquid component inlets (18, 20 and 22). Rotatable piston (24) has a notched portion (30). Relative lengths of time the notched portion (30) is opposite the inlets (18, 20 and 22) determine the proportion of liquid components supplied at each inlet port (18, 20 and 22) in the solvent mixture. Rotation of the piston (24) in the chamber (12) mixes the liquid components introduced through the inlet ports (18, 20 and 22). Stepper motor (32) is controlled by microprocessor (52) driven control system (50) to position the notched portion (30) at the inlet ports (18, 20 and 22) for variable lengths of time.

FIG.

SOLVENT PROPORTIONING AND MIXING APPARATUS AND SYSTEM

BACKGROUND OF THE INVENTION

1. Field of the Invention

This invention relates to a novel apparatus and system for proportioning and mixing a solvent which is made up of a plurality of liquid components. More particularly, it relates to such an apparatus and system in which the liquid components of the solvent are both proportioned and mixed in a single chamber.

2. Description of the Prior Art

It is conventional practice in liquid chromatography to introduce samples to be analyzed to a chromatographic column in a carrier solvent. The carrier solvent typically consists of a mixture of two or more liquid components. During the analysis, the proportions of the liquid components in the solvent may be varied on a linear or non-linear time varying basis. A variety of techniques are known in the art for providing such varying solvent mixtures to the chromatographic columns. For example, U.S. Pat. No. 4,063,077 discloses programmable control circuitry for a valve to access liquid components of a solvent mixture during a defined cycle of operation to proportion the components of the solvent on the basis of the time within the cycle of operation that each component is accessed by the valve. The accessed components are supplied through the valve and a pump to a separate mixer to produce the solvent mixture. U.S. Pat. No. 4,239,623 discloses a system in which each liquid component of the solvent is accessed by separate valves, operated by separate stepper motors. U.S. Pat. No. 4,310,420 discloses a system in which the liquid components of the solvent are separately accessed by solenoid valves. While these prior art systems have proved to be highly suitable for supplying chromatographic solvents, they are both complex and bulky because the liquid component proportioning and mixing are accomplished separately. Because of their size, they also have a delayed response time for the variations in solvent composition. For reasons of compactness and cost, there is a need for a simpler apparatus and system for proportioning and mixing liquid components of a solvent.

SUMMARY OF THE INVENTION

Accordingly, it is an object of this invention to provide an apparatus for proportioning and mixing a solvent including a plurality of liquid components in which both the proportioning and the mixing are carried out in a single unit.

It is another object of the invention to provide such a solvent proportioning and mixing apparatus of reduced size.

It is a further object of the invention to provide such a solvent proportioning and mixing apparatus which will carry out highly accurate, uniform mixing of the liquid components comprising the solvent.

It is still another object of the invention to provide a system incorporating such a solvent proportioning and mixing apparatus with a reduced response time for varying proportions of the liquid components comprising the solvent.

The attainment of these and related objects may be achieved through use of the novel solvent proportioning apparatus and system herein disclosed. The apparatus of this invention proportions and mixes a solvent

including and mixing a plurality of liquid components. The apparatus has a chamber with a plurality of inlet ports, each connected to supply one of the plurality of liquid components of the solvent. A member is mounted in the chamber and is movable to different positions for selectively permitting entry of the liquid components to the chamber through the plurality of inlet ports. Different lengths of time the movable member is positioned to allow entry of each liquid component through each of the plurality of inlet ports serves to proportion the plurality of liquid components in the solvent.

Movement of the movable member within the chamber serves to mix the plurality of liquid components. There is an exit from the chamber for the proportioned and mixed solvent. In a preferred embodiment of the invention, the movable member is rotatable in the chamber and is dimensioned to be in close proximity to a wall defining the chamber and thus effecting a seal. The movable member has a notched portion which is positioned to be accessed by each of the plurality of inlet ports as the movable member rotates.

By varying the relative length of time each of the inlet ports is accessed by the notched portion, the amount of each liquid component in the solvent can be varied in a closely controlled manner to constitute from 0 to 100% of the solvent in small and accurate increments.

In practice, the movable member is preferably driven by a stepper motor. The stepper motor is connected to programmable control circuitry which varies the rate the stepper motor moves the movable member and/or the length of time the movable member is stopped to allow entry of a component into the chamber to provide variable lengths of time the movable member is positioned to allow entry of each liquid component through each of the inlet ports. Through use of a suitable program, a user may therefore vary the proportions of the liquid components making up the solvent. Because the solvent is both proportioned and mixed in a single chamber, the apparatus of this invention is compact in size and rapid in response.

The attainment of the foregoing and related objects, advantages and features of the invention should be more readily apparent to those skilled in the art, after review of the following more detailed description of the invention, taken together with the drawings, in which:

BRIEF DESCRIPTION OF THE DRAWINGS

FIG. 1 is a perspective view of apparatus in accordance with the invention, with partial cutaways to show interior detail.

FIG. 2 is a cross-section view taken along the line 2-2 in FIG. 1.

FIG. 3 is a cross section view taken along the line 3-3 in FIG. 2.

FIG. 4 is a logic and circuit schematic of a portion of a system in accordance with the invention.

FIG. 5 is a flow diagram for software used in the system of the invention.

FIG. 6 is a flow diagram of further software used with the invention.

DETAILED DESCRIPTION OF THE INVENTION

Turning now to the drawings, more particularly to FIGS. 1 to 3, there is shown apparatus 10 in accordance with the invention. The apparatus 10 includes a cham-

ber 12, formed by a ceramic tube 14, rotary ball bearing 16, dynamic seal 17 and bearing retainer 19. Liquid component inlet ports 18, 20 and 22 are positioned circumferentially around the tube 14 near the center of its length. A ceramic or other suitable rotatable piston 24 is disposed axially within the chamber 12, through the dynamic seal 17, past the inlets 18, 20 and 22. End 26 of the piston 24 terminates short of end 28 of the chamber 12, thus forming a mixing zone in the chamber 12. Piston 24 has a slotted portion 30 extending from end 26 past the inlet ports 18, 20 and 22. Rotatable piston 24 fits into chamber 12 with a close tolerance, e.g., 500 millionths of an inch. As a result, fluid flow inlet through inlet ports 18, 20 and 22 is blocked by the rotatable piston 24, except when slotted portion 30 is opposite one of the inlet ports 18, 20 and 22. Rotatable piston 24 is connected to stepper motor 32, which is capable of rotating the piston 24 in response to stepping drive pulses up to a relatively high average rate of rotation, such as 300 rpm, through a flexible coupling 33.

In operation, liquid components to be proportioned and mixed are separately supplied to the liquid component inlet ports 18, 20 and 22. Stepper motor 32 rotates the rotatable piston 24 to position the slotted portion 30 opposite the inlet ports 18, 20 and 22. A liquid component is permitted to enter the chamber 12 when the slotted portion 30 is opposite its inlet 18, 20 or 22. The relative lengths of time that the slotted portion 30 is opposite each inlet port 18, 20 and 22 determines the proportion of each liquid component in the resulting solvent mixture. In this operation, the slotted portion 30 is allowed to dwell at each inlet port 18, 20 or 22 for the required time interval. If a liquid component is to be omitted from a solvent composition, its inlet port 18, 20 or 22 can be omitted in the rotation of the piston 24, i.e., the piston 24 may oscillate between two of the inlet ports. The dwell times of the slotted portion 30 at the inlet ports 18, 20 and 22 can be varied with time to give essentially any varying solvent composition profile, as required for liquid chromatography or other application requiring a time varying solvent composition mixture.

FIG. 4 is a block, logic and circuit schematic diagram of a control system 50 for the stepper motor 32. A microprocessor integrated circuit 52, such as an Intel 8080 or 8085 type microprocessor integrated circuit is used to provide control logic for the system 50. A keyboard 54 or other means for providing desired solvent composition input is connected to the microprocessor 52 by lines 56. A position sensor, such as a Hall effect sensor 58 (see also FIG. 2) is connected to provide a position input for the piston 24 on line 60 to the microprocessor 52. An A output from the microprocessor 52 is supplied on line 62 as both inputs of NAND gate 64. An A' input is supplied on line 66 to NAND gate 68. The other input to NAND gate 68 is supplied by the output of NAND gate 64 on line 70. A B output from the microprocessor 52 is supplied on line 72 as both inputs to NAND gate 74. A B' output from the microprocessor 52 is supplied on line 76 as one input to NAND gate 78. The other input to NAND gate 78 is supplied by the output of NAND gate 74 on line 80. The outputs of NAND gates 64, 68, 74 and 78 are respectively supplied on lines 82, 84, 86 and 88 as inputs to inverter buffer/drivers 90, 92, 94 and 96. The inverter buffer/drivers 90, 92, 94 and 96 supply their outputs on lines 98, 100, 102 and 104, respectively, to the bases of transistors Q1, Q2, Q3 and Q4. The collectors of transistors Q1, Q2, Q3 and Q4 are respectively connected by lines 106, 108, 110 and 112 to

coils 114, 116, 118 and 120 of the stepper motor 32. Each coil 114, 116, 118 and 120 is also connected to a +12 volt potential source by lines 122, 124, 126 and 128. Diodes D1, D2, D3 and D4 are respectively connected between the emitters and collectors of transistors Q1, Q2, Q3 and Q4 by lines 130 and 132, 134 and 136, 138 and 140, and 142 and 144.

In practice, the NAND gates 64, 68, 74 and 78 may be implemented with a 7400 type quad 2-input NAND integrated circuit. The inverter buffer/drivers 90, 92, 94 and 96 may be implemented with a 7406 type hex inverter buffer/driver integrated circuit. Transistors Q1, Q2, Q3 and Q4 may be implemented with 2N2222 type transistors, and the diodes D1, D2, D3 and D4 may be implemented with 1N4001 type diodes. As shown, the stepper motor 32 is connected for unipolar operation.

FIG. 5 is a software flow diagram for a suitable control program for practising the invention with the microprocessor 52. Decision block 200 determines if there is an entry from keyboard 54. Decision block 202 determines whether the entry is a digit, i.e., whether it is a data entry. Decision block 204 determines whether the input is from the enter function key of the keyboard. Decision block 206 tests the validity of digit entries. Decision block 208 determines whether a digit entry has been selected for a B component, supplied to inlet port 22 (FIGS. 1-3). Decision block 210 determines whether a digit entry is for a C component, supplied to inlet port 20. Decision block 212 tests the validity of B and C component digit entries, and if valid, the proportion of component A is calculated by subtracting the B and C values from 100. Decision block 214 determines whether a function key selecting execution of an entered solvent composition has been selected. If so, the piston 24 is rotated to A inlet port 18, found on the basis of a suitable input from Hall effect sensor 58 to the microprocessor 52.

A timer subroutine, shown in FIG. 6, is then started. Decision block 220 determines whether the gradient count equals zero. Decision block 222 determines whether the slotted portion 30 of the piston 24 is at the A port 18. If the notched portion 30 is at the A port 18, decision blocks 224 and 226 test whether the gradients for ports B and C are set at zero. If yes, the gradient count is updated for the A gradient, and the program jumps to timemode at 228 to start timing for component A. When decision block 220 determines that the gradient count for component A equals zero, decision blocks 222 and 224 are executed to determine whether the notched portion 30 should be stepped to B component port 22. If so, subroutine FORW at 230 is executed. Eight steps of the stepper motor 32 represent 120 degrees of revolution and move the notched portion 30 to B inlet port 22.

When decision block 220 determines that the gradient count equals zero and decision block 222 determines that the notched portion 30 is not at A port 18, decision blocks 232 and 234 determine whether the notched portion should be stepped to C component inlet port 22. If the C gradient is not equal to zero, the program again steps to subroutine FORW at 230. When gradient C equals zero, the program goes to decision block 236. If the A gradient is not equal to zero, the program jumps to reverse subroutine at 238 to return the notched portion 30 to A component inlet port 18. If the A gradient is equal to zero, the B gradient is set and timing for the B inlet 20 is carried out. Decision blocks 240 and 242 operate in an analogous fashion.

The attached assembly language program listing for the Intel 8080 or 8085 type microprocessor provides further details on the implementation and operation of the invention.

In summary, the apparatus 10 and system 50 of this invention steps slotted portion 30 of piston 24 in a forward or reverse direction among solvent ports 18, 20 and 22 at a relatively high average motor speed in order both to define a desired solvent mixture and to provide good mixing of the liquid components of the mixture. The system 50 further allows a liquid inlet port 18, 20 or 22 to be avoided if the desired amount of its liquid is zero. The system further provides a sensor 58 for detecting the position of the moving piston 24 as it is rotated.

It should now be readily apparent to those skilled in the art that a solvent proportioning and mixing apparatus and system capable of achieving the stated objects of the invention has been provided. A solvent consisting of

5 mixed liquid components may be both mixed and proportioned in a single unit of reduced size which will mix the liquid components uniformly. As a result, a reduced response time for varying proportions of the liquid components in the solvent may be achieved.

10 It should further be apparent to those skilled in the art that various changes in form and details of the invention as shown and described may be made. For example, a servomotor could be substituted for the stepper motor 32. It is intended that such changes be included within 15 the spirit and scope of the claims appended hereto.

What is claimed is:

1. A system for proportioning and mixing a solvent including a plurality of liquid components, which comprises a chamber having a plurality of inlet ports each connected to supply one of the plurality of liquid components, a member mounted in said chamber and being movable to different positions for selectively permitting entry of the liquid components to said chamber through said plurality of inlet ports, different lengths of time the movable member is positioned to allow entry of each liquid component through each of said plurality of inlet ports serving to proportion the plurality of liquid components, and movement of said movable member within said chamber serving to mix the plurality of liquid components, an exit from said chamber for the proportioned and mixed solvent, a motor with positional feedback

connected to move said movable member, means connected to sense a position of said movable member, to determine a next position of said movable member, and to provide variable lengths of time the movable member is positioned to allow entry of each liquid component through each of said plurality of inlet ports.

2. The apparatus of claim 1 in which said movable member is rotatably movable in said chamber, said movable member having a notched portion, said movable member serving to block entry of a liquid component through each of said inlet ports except when said notched portion is positioned at one of said inlet ports.

3. The apparatus of claim 2 in which said movable member is dimensioned to be in close proximity to a wall defining said chamber.
